UNITED STATES PATENT OFFICE.

ARTHUR W. WARNER, OF SEWICKLEY, PENNSYLVANIA, ASSIGNOR TO RITER-CONLEY MANUFACTURING COMPANY, OF PITTSBURGH, PENNSYLVANIA, A CORPORATION OF NEW JERSEY.

CONTROL MECHANISM FOR GAS-GENERATING APPARATUS.

1,270,472.

Specification of Letters Patent. Patented June 25, 1918.

Application filed February 3, 1915. Serial No. 5,866.

To all whom it may concern:

Be it known that I, ARTHUR W. WARNER, a citizen of the United States, residing at Sewickley, in the county of Allegheny and 5 State of Pennsylvania, have invented certain new and useful Improvements in Control Mechanism for Gas-Generating Apparatus, of which the following is a specification.

10 My present invention relates to improvements in control mechanism for gas generating apparatus, relating more particularly to means whereby the operator of the retort-charging machine is able to control the 15 exhauster mechanism and thereby permit a substantial balancing of pressures at the off-take of the retort to be charged.

In gas generating plants such as contemplated by the present invention, it is the 20 practice to arrange the gas retorts in benches, the retorts being generally arranged in vertical and horizontal alinement. In charging and discharging the retorts it is a common practice to provide successive 25 charging operations in horizontal rather than vertical rows, thereby enabling the charging machine to travel from one retort to another without shifting the position of the charger vertically between chargings, 30 excepting when the retorts of a different horizontal row are to be charged.

As is well known, the retorts are connected to a main by stand-pipe connections, and during the discharging and charging operations 35 the retort doors are necessarily open. If the pressure in the retorts exceeds that of the atmosphere, gas will escape. If, on the other hand, the pressure within the retort is less than that of the atmosphere, 40 there will be an inrush of the air into the retort (which will find its way to the main through the standpipe connection). To equalize these pressures it is the general practice to employ an exhauster mechanism 45 by means of which the variations of pressure are controlled.

In the prior patent to Carpenter and Warner, No. 1,138,727, May 11, 1915, a disclosure is made of apparatus by means 50 of which the exhauster mechanism may be operated to provide substantial equilibrium between the interior of the retorts of a predetermined horizontal row and the atmosphere by varying the pressure at which

the system is operating. This action is accomplished by an operator who, having before him information relative to the pressures of the several horizontal rows, is able to so adjust the exhauster mechanism as to vary the exhauster action to cause substantially equal pressure between the row of retorts and atmosphere, the arrangement being such as to permit him to provide this operation at a point remote from the exhauster mechanism.

While this particular arrangement provides entirely satisfactory results, I have found that, through changes and additions to the apparatus, the operation may be so changed as to reduce the cost thereof, as 70 well as to further safeguard the charging machine operator at the time of opening the retort lid.

For instance, the control of the above mentioned patent, is generally located at 75 the end of the retort house and operated by a separate operator, who adjusts the apparatus to the approximate pressure of the row to be charged and then, if more accurate adjustment is desired, attempts additional adjustments through the information derived from the flame when the lid is "cracked." Where the stack of retorts is long and high, it is a difficult matter for him to see the result of his adjustment, 85 especially where no flame is present, thus leaving open the possibility of a non-balanced condition. As the adjusting effect is similar throughout the row, there is a possibility that the difference in action of different benches may result in a balanced condition at one retort and an unbalanced condition at other retorts in the same row.

In the present invention the manipulation of the exhauster mechanism for charging operations is performed by the charging machine operator who, by reason of his duties in opening the lid, is in a position to accurately note the effect of the adjustments and is thus able to provide the proper 100 adjustments. This has the effect of making the control individual to each retort, as will be understood from the following.— The machine operator brings his machine to the point where he is in position to open 105 the lid of the retort to be charged, after which the lid is "cracked," i. e., unsealed though still locked. If the result is a heavy

flame, the retort pressure is too great, and the operator simply manipulates a button or switch on his machine to increase the speed of the exhauster, the effect of which 5 is to reduce the retort pressure and thus decrease the flame, this action continuing until the proper flame is produced, whereupon, he is aware that the lid may be opened with safety, the pressures being balanced; if the 10 "cracking" operation does not produce a flame, he is aware that the retort pressure is too low, and consequently decreases the speed of the exhauster until the flame appears at its proper size. He then charges 15 the retort, closes the lid and proceeds to the next retort where the operation is repeated. The services of the additional exhauster operator heretofore employed can thus be dispensed with.

20 To these and other ends, the nature of which will be readily understood as the invention is hereinafter disclosed, my invention consists in the improved construction and combination of parts hereinafter fully 25 described, illustrated in the accompanying drawings, and more particularly pointed out in the appended claims.

In the accompanying drawings, in which 30 similar reference characters indicate similar parts in each of the views,

Figure 1 is a diagrammatic view showing a portion of a stack of retorts in vertical section, an exhauster mechanism, a variable control therefor, shown partially in section, 35 a pressure-control mechanism, a charging machine, and connections for providing the operations of the present invention;

Fig. 2 is a diagrammatic view showing a portion of a retort and stand-pipe with the 40 retort lid in "cracking" position and also open, and the charging machine in position to permit the machine operator to open the retort; and

Fig. 3 is a detail view showing a face 45 view of the retort lid.

Referring particularly to Fig. 1, A designates a bench structure having retorts *a*, the latter having mouth-pieces *a'* adapted to be closed by lids *a''*, the mouth-pieces at the 50 front of the bench being in communication with a stand-pipe *B*. The stand-pipe is shown as communicating with a main *C* leading to an exhauster *D*, the speed of which is regulated in a suitable manner, the 55 drawing showing the regulating means in the form of a valve controlling member *d* adapted to be moved through the movements of a lever *d'* the latter, in turn, being operated by mechanism connected to a variable apparatus, such, for instance, as a floating bell *d''* having its interior in open communication with the main *C*. As will be understood, the variations in pressure occurring in the main *C* will affect the pressures 60 within the bell and thus provide movements 65

to the prime mover for the exhauster. This arrangement provides for a control which tends to maintain the pressure of the main at an approximately constant standard, based, however, on a predetermined pressure as such standard.

In the above mentioned Carpenter and Warner patent, provision is made for changing this standard at will by the use of a shiftable weight, the movements of the 75 weight being provided by a reversible motor, the operation of the motor being controllable. This general arrangement is shown diagrammatically in Fig. 1, in which

e represents the weight adapted to be threaded along a spindle *e'*, the movements of the latter being provided by a motor *e²*, the operations of which are adapted to be controlled by a reversing switch structure or other controller indicated at *e³*. The motor 80

is preferably of the three phase type, and in Fig. 1, I have shown the source of supply at *E*. The reversing switch *e³* may be located at any suitable point, and in the embodiment of the present invention is simply 85 an auxiliary structure. This auxiliary structure is located at a suitable point remote from the exhauster mechanism, as for instance, in the retort house or in the office of the superintendent of the plant, suitable 90 gages, etc., being generally provided in order that the desired pressure readings, etc., may be had at a point where the exhauster mechanism may be readily manipulated to meet the various conditions of operation. It 95 will be readily understood that by the use of the reversing switch, the direction of the rotation of the motor *e²* can be varied as desired.

F designates a charging machine adapted 105 to travel to and fro in front of the retorts on track *f*, suitable travel mechanism being provided for the purpose, which mechanism may be of the type shown in the patent to Carpenter and Hibbard, No. 1,144,165, June 110 22, 1915, the particular travel mechanism employed being immaterial so far as the present invention is concerned.

The charging machine is shown as provided with a platform *f'* mounted to move 115 vertically by means of threaded rods *f''* adapted to be operated in a suitable manner as by the hoist mechanism shown in the said Carpenter and Hibbard patent. Neither of these operating means is shown. Nor is the mechanism for operating the charger, indicated at *G*, disclosed in the present application, since it forms no particular part of the present invention. The travel, hoist and charger operations are referred to simply as 120 illustrating the manner in which the present invention operates when applied to a charging machine in general use.

As shown by Figs. 1 and 2, the operating platform extends to a point adjacent to the 125

front of the retorts, thereby enabling the machine operator to manipulate the retort lids. Since the platform is adjustable vertically, it will be seen that such adjustment 5 will place the operator at a proper point relative to the retort to be charged, it being understood that the machine has traveled to the proper position lengthwise of the stack, and the platform moved to the particular 10 elevation desired.

H designates a suitable controlling device which may be in the form of a reversing switch, or a push button arrangement, as desired, both forms being well known in the 15 art. This control mechanism is located on the platform *j'* at a point readily accessible to the operator when in proximity to the retort lids. This control mechanism is adapted to be operatively connected to two of the 20 three leads running to the motor *e²*, these two leads providing for reversal of the motor, the third lead running direct to the motor. Since the motor *e²* is located at a fixed point, while the machine is adapted to travel, I preferably provide the connections 25 between the controller and the motor by the use of trolleys, indicated at *h*, the drawing showing four of these trolleys to provide the complete circuit between the supply, controller, and motor.

As shown in Fig. 1, the two controls indicated at H and at *e³* respectively, are shown as connected up in parallel in the motor circuit. Obviously, the control *e³* may be omitted 35 without affecting the operation from the charging machine.

In Figs. 2 and 3, I have shown more particularly a detail structure of a retort mouth-piece *a'* having a lateral *a³* which 40 leads to the stand pipe, this providing the path for the gas from the retort *a* to the stand-pipe B. I have also shown the lid *a²* as provided with locking means, indicated at J, and having a handle *j*, a locking bar 45 *j'*, and a latch *j²*. The particular arrangement of the locking means is immaterial, the form shown being that disclosed in the patent to Henry A. Carpenter, No. 1,149,026, August 3, 1915, the structure being so arranged 50 as to permit "cracking" of the lid, the latter being shown in this position in full lines in Fig. 2. This position of the lid is obtained by moving the handle *j* with its cam in a manner to release the tight fit of 55 the lid with respect to the mouth piece.

In Fig. 2 I have shown the platform in approximate position for operation with respect to the retort shown in section, the charging machine having been moved to 60 this position, and it is assumed that the operator has thrown the lever or handle *j* and thus released the lid to an extent sufficient to permit communication between the atmosphere and the mouth piece. When the 65 operator has placed the lid in this position,

he applies a torch to the space between the lid and the mouth piece for the purpose of igniting any gas which may be escaping through this space.

Since the gas, during the carbonization 70 period in the retort, flows from the retort through the mouth piece *a* and lateral *a³* into the stand pipe B, it will be understood that if the exhaust mechanism is providing a vacuum action insufficient to produce 75 an equilibrium between the atmosphere and the pressure in the retort when this "cracking" operation takes place, the excess pressure within the retort will cause the gas to escape through the space between the mouth 80 piece and the lid and provide a material flame at the face of the retort and if the lid were opened at this time, the excess pressure would cause the flame to be forced out into the face of the operator. When this 85 excessive flame appears, it indicates to the operator an excessive pressure, and he thereupon operates his controller in such manner as to increase the speed of the exhaust prime mover, this action being continued 90 until the flame has reached the proper point, a standard in this respect being a small flame within the space between the lid and mouth piece and slightly exposed at the edge of the lid. When this point is reached, the lid 95

may be safely opened, since pressure within the retort is substantially in equilibrium with the atmosphere. Should no flame appear when the torch is applied, the operator knows that the pressure within the retort 100 is less than that of the atmosphere by reason of the exhaust providing a too great vacuum action for the particular retort; consequently, the operator will then manipulate the controller in such manner as to 105 decrease the vacuum action, this result being obtained by shifting the weight *e* in the direction to decrease the speed of operation of the exhaust, thereby building up the pressure within the retort until it is in substantial equilibrium with that of the atmosphere, this fact being indicated by a flame appearing at the crack. By manipulating the controller, this flame can be brought to the proper condition after which 110 the retort lid is opened, and the charging operation takes place, the machine being moved to place the charger in alignment with the retort after such opening of the lid. After the charge has been placed in 115 position and the charger returned, the machine is again moved to position where the operator is able to close the lid, after which the machine is traveled to the next retort to be charged.

The improved arrangement places the observer (the operator) in close proximity to the retort which is to be opened, and therefore in the best possible position to determine when equilibrium in pressure is 120 125 130

reached. As a result, the operator is able to provide this equilibrium with rapidity and exactness, and it is possible to operate the gas generating apparatus without reference to 5 any valve structure for controlling the port leading to the stand pipe from the lateral, the equalization of pressure through regulating the exhauster to the individual retort placing the stand pipe pressure at the opening 10 from such retort in such condition as will practically prevent the entrance of atmosphere into the stand pipe through the open mouth piece. Since only one retort is being charged at a time, the slight variations in pressures provided by this regulation 15 of the exhauster mechanism to suit the needs of an individual retort does not materially affect the operations of the remaining retorts.

20 During the retort charging periods, the adjustments necessary to either increase or decrease the pull of the exhauster are made by the charging machine operator through the medium of controller H , and hence only 25 one operator is required, and that single operator is right at the retort being operated upon and hence in the best possible position to adjust the exhauster to that retort. Where, as heretofore, the adjustment is 30 made from a central station, an additional operator is required who is stationed at such distance from the retorts that accurate adjustment for each retort is rendered impossible. This is particularly true where 35 the stack is long and many of the retorts are at a considerable elevation from the operating floor. In addition to accurately controlling the operation and thereby preventing the escape of gas or the admission 40 of air, a further and very important result of the invention is the safety of the charging machine operator who must manipulate the retort doors, particularly those at considerable elevation which cannot be reached 45 from the floor. With no exhauster controlling means at hand, he would be unable to check a strong outward flame so that his position in front of such a retort would be extremely hazardous. By means of the 50 present invention the conditions individual to each retort may be met, whereby the operation is rendered uniform for all the retorts and the safety of the operator is assured.

55 If both of the controllers H and e^s are employed, a primary or general adjustment may be had by means of e^s , and the variations individual to each retort effected by controller H . Or the entire control may be accomplished by the latter if it is desired to eliminate controller e^s .

What I claim is:—

1. In gas generating apparatus, the combination of a retort and a retort lid, an ex-

hauster for the retort, a regulator for varying the action of the exhauster, and regulator controlling means having position adjacent to the retort lid, whereby the lid and the controller may be manipulated by a single operator.

2. In gas generating apparatus, the combination of a retort and a retort lid, an exhauster for the retort, a regulator for varying the action of the exhauster, a retort charging machine provided with an operator's station from which the retort lid is accessible, and a controller for the exhauster regulator, said controller located on the charging machine and accessible from the operator's station.

3. In gas generating apparatus, the combination of a plurality of retorts and retort lids, an exhauster common to the retorts, a regulator for varying the action of the exhauster, a charging machine adapted to be moved to position for coöperating with any retort, the machine having an operator's station movable therewith and from which the lid of the retort to be charged is accessible, and a controller for the exhauster regulator, said controller located on the charging machine and accessible from the operator's station.

4. In gas generating apparatus, the combination of a plurality of retorts and retort lids, mechanism at the exterior of and movable relatively to the retorts and thereby adapted to be positioned for coöperation with any one retort, said mechanism having an operator's station movable therewith and from which the lid of the retort to be operated upon is accessible, an exhauster common to the several retorts, a regulator for varying the action of the exhauster, and a controller for the regulator mounted on said movable mechanism and accessible from said operator's station.

5. In gas generating apparatus, the combination of a retort and a lid therefor, an exhauster for the retort, two interchangeably operating controllers for the exhauster—one located at a distance from the retort and the other closely adjacent to the retort, whereby by means of the last mentioned controller a single operator may without changing his position manipulate the lid and adjust the exhauster.

6. In gas generating apparatus, the combination of a plurality of retorts and retort lids, exhauster mechanism common to the retorts, a traveling charging machine adapted to be positioned for coöperating with any retort, the charging machine having an operator's station movable therewith and from which the lid of the retort to be operated upon is accessible, and two interchangeably operating controllers for the exhauster—one having non-traveling position

and the other located on the charging machine and accessible from the operator's station.

7. In gas generating apparatus, the combination with a retort, and a retort charging machine, of means operative from the machine for manipulating the retort pressure to place it in substantial equilibrium with the atmosphere.

10 8. In gas generating apparatus, the combination of a retort heating structure, retorts located in said structure and spaced apart horizontally and vertically and accessible from the exterior of the furnace struc-

ture, a retort charging machine adjustable 15 both horizontally and vertically relatively to said structure for serving the several retorts, an exhauster common to the several retorts, and means located on the charging machine and movable horizontally and vertically therewith for controlling the operation of the exhauster.

In testimony whereof I affix my signature in presence of two witnesses.
